UNITED STATES PATENT OFFICE

113,799

DESIGN FOR A DRESS

Jean Bensi, New York, N. Y.

Application December 17, 1938, Serial No. 81,831

Term of patent 3½ years

To all whom it may concern:

Be it known that I, Jean Bensi, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific, tucked yokes on the shoulders, in association with the pleated skirt and the specific belt member, as shown.

I claim:

The ornamental design for a dress, substantially as shown and described.

JEAN BENSI.
